UNITED STATES PATENT OFFICE.

THOMAS VILLAGE, OF WEST MERIDEN, CONNECTICUT, ASSIGNOR TO MERIDEN
MALLEABLE-IRON COMPANY, OF SAME PLACE.

DESIGN FOR BRACKETS AND CHANDELIERS.

Specification forming part of Design No. 5,091, dated July 4, 1871.

To all whom it may concern:

Be it known that I, THOMAS VILLAGE, of West Meriden, in the county of New Haven and State of Connecticut, have invented a new and original Design for Brackets and Chandeliers; and I do hereby declare that the following is a full, clear, and exact description thereof, which will enable others skilled in the art to make and use the same, reference being had to the accompanying drawing forming part of this specification.

Figure 1 is a side elevation of the bracket or chandelier-arm and basket; also, a wall-piece for supporting them on the side of a wall. Fig. 2 is a front view of the wall-piece, and Fig. 3 is a plan view of the bottom of the basket.

Similar letters of reference indicate corresponding parts.

The design for the wall-piece, Fig. 2, embraces the oval-ribbed piece *a* projecting from the center of the four beveled and indented sides *b b c c* of the plate *B*, surrounded by the plain bars *e f g*, two of the said sides having the raised figures *i* and the other the ones *h*, and the upper and lower edges having the attaching-plates *l*, all as shown. The design for the arm embraces the in-

dented sides with the raised chain *k*, plain edges *j*, and squares *m*, the latter with inclosed raised figures *n*, the pendent acorn-shaped piece *o*, vertical projection *p*, scroll-shaped piece *q* with the pendant *r* and top piece *s*, the pendants *t* and *u*, and the scroll-piece *v*, all substantially as shown. The design for the basket comprises the pointed and perforated side *x*, the vertical plane surface *y*, concave indented surface *z*, plane surface *z¹ z²*, and the perforated bottom *z³*, all as shown.

The arm and basket are to be used either in connection with a wall-piece as a bracket or as parts of a chandelier, the arm being attached to the center-piece of a chandelier.

I claim as my invention—

1. The design for the wall-piece, substantially as shown.
2. The design for the bracket or chandelier-arm, substantially as shown.
3. The design for the basket for a bracket or chandelier-arm, substantially as shown.

THOMAS VILLAGE.
